UNITED STATES PATENT OFFICE

2,499,345

AXE WITH DETACHABLE BLADE

Epps Joseph Adams, Augusta, Ga.

Application January 3, 1946, Serial No. 638,727

1 Claim. (Cl. 145—2)

1

My invention appertains to an axe construction in which the head into which the handle is inserted, and the blade are separable and preferably of different material; that is, the head may be made of soft or cheaper grade of iron, while the blade is made of tool steel with an edge which is suitable for taking a certain amount of hardening and grinding.

The following advantages of this construction should be noted.

The axe head into which the axe handle is attached in the usual manner should practically last indefinitely, provided that a reasonable amount of care is used to protect it from rusting, bending or breaking.

The blade, made of costlier material, is very durable as regards wear, and keeps its edge and sharpness without regrinding for a considerable time. Being of small size, as compared with the entire axe, it can be manufactured cheaply.

When one blade has been worn out, the securing of a new blade to an old head, needing no fitting, as all parts would be standard, is equivalent to obtaining a brand new axe at a considerably reduced price.

Other advantages will occur from reading the following description with the attached drawing.

One embodiment of the invention is illustrated on the drawing in which:

Figure 1 is a perspective view of the axe assembled with a portion of the handle.

Figure 2 is a section along line 2—2 of Figure 1.

Figure 3 is a side elevation of the axe-head alone.

Figure 4 is a vertical section along line 4—4 of Figure 3, slightly enlarged.

Figure 5 is a side elevation of the axe-blade alone.

Figure 6 is a vertical section taken along line 4—4 of Figure 5.

In the drawing, like reference numerals denote like details in the different views.

The head of the axe is denoted by numeral 10 having a hole 12 therethrough to accommodate a conventional axe-handle 11. At the lower end of the head which is slightly more than half the length of an ordinary axe, a blade 13 is firmly secured. When assembled together, the head 10 and the blade 13 have a smooth taper from the flat top 14 down to the sharp edge 15 of the blade 13. A mortice cut 16 is formed therein by an inclined cut surface 17 which slants from an undercut edge 18 on the right side, as seen in Figure 2, down to a similar edge 19 on the left 55

side of the axe. This mortice cut 16 tapers upwardly from the bottom edge 19 of the axe head to the top edge 18 thereof.

The blade 13 has a correspondingly tapered tongue 20 made to fit tightly in the mortice cut 16 in the axe-head. After wedging in the blade 13 firmly in the mortice 16 it is additionally fastened by a transverse screw 21, which is threaded as at 22 in the heavy middle part of the axe. This screw 21 has preferably a beveled head which is countersunk as at 22 in the blade, which is not threaded.

After the head and blade are thus assembled, the side faces should be ground and the edge 15 sharpened.

It is to be understood that the invention as here disclosed is not limited to the details here described and shown but that the same may be varied without departing from the spirit of the 20 invention as defined by the subjoined claim.

I claim:

An axe having a detachable blade and comprising a head having side faces and first and second end portions, a cut-out in one side face 25 of the head and at the second end of the head, said cut-out including an inclined bottom surface sloping from one side face of the head to the other side face of the head, said cut-out also including a pair of side walls diverging 30 toward the second end of said head, the side walls of said cut-out being dovetailed, said blade having a tongue, said tongue being wedge-shaped in two planes at right angles to each other, said tongue fitting tightly in said cut-out and including 35 a pair of converging dovetailed side edges contacting the side walls of said cut-out.

EPPS JOSEPH ADAMS.
